UNITED STATES PATENT OFFICE.

FRANCIS H. WITTSTEIN, OF NEWARK, NEW JERSEY.

DESIGN FOR A FINGER RING.

Application filed July 3, 1923. Serial No. 6,662. Term of patent 3½ years.

To all whom it may concern:

Be it known that I, FRANCIS H. WITTSTEIN, a citizen of the United States, and a resident of Newark, in the county of Essex and State of New Jersey, have invented a new, original, and ornamental Design for Finger Rings, of which the following is a specification, reference being had to the accompanying drawing, forming part thereof.

Figure 1 is a front elevation of a finger ring showing my new design;

Figure 2 is an edge elevation of the same viewing it from one side, and

Figure 3 is a top plan view of the ring.

I claim:

The ornamental design for a finger ring, as shown.

FRANCIS H. WITTSTEIN.
